UNITED STATES PATENT OFFICE.

DESIGN FOR A FONT OF PRINTING-TYPE.

SPECIFICATION forming part of Design No. 12,933, dated May 16, 1882.

Application filed November 18, 1881. Term of patent 3½ years.

To all whom it may concern:

Be it known that I, CHARLES E. HEYER, a citizen of the United States, residing at No. 438 Madison street, in the city of Chicago, county of Cook, and State of Illinois, have invented and produced a new and original Design for a Font of Printing-Types, of which the following is a specification, reference being had to the accompanying typographical illustration, forming a part hereof.

The character of the design is of an extended letter of a so-called "Celtic" style; and it consists of capitals, points, and figures, as shown in the accompanying illustration.

15 My design differs from a similar style of let-

ter, in that the characters B, C, D, E, F, G, O, P, Q, R, S, and & and figures 2, 3, 5, 6, 7, 8, 9, and 0 have no severed top lines with dot termination, and characters A H I J K L M N U V W X Y and figures 1 and 4 have no curled 20 hair-lines with dot termination.

I claim—

The design for a font of printing-types, as described.

Signed at Chicago, in the county of Cook 25 and State of Illinois.

CHARLES E. HEYER.
